UNITED STATES PATENT OFFICE

RALPH H. MAJOR, OF KANSAS CITY, KANSAS, ASSIGNOR TO ELI LILLY AND COMPANY,
OF INDIANAPOLIS, INDIANA, A CORPORATION OF INDIANA

BLOOD-PRESSURE-LOWERING SUBSTANCE AND PROCESS OF PRODUCING IT

No Drawing.

Application filed April 10, 1926. Serial No. 101,191.

It is the object of my invention to obtain from the liver an effective product containing in a high degree of concentration, and in sufficient purity so that it may be repeatedly administered to human beings without dangerous shock or undue toxic effects, the active principle or hormone which reduces high blood pressure (hypertension) and relieves certain subjective symptoms commonly associated with hypertension, such as headache, insomnia, nocturia, tinnitus, etc.

Previous investigators have suggested that the liver contains or secretes a substance or hormone which has a depressor effect on blood pressure and/or relieves such subjective symptoms. Indeed, previous investigators have produced extracts from the liver that exerted some depressor action. The following references are some of those that describe this previous work:

1. La Presse Medicale, Mercredi 24 Mai 1922, by H. Roger;
2. The American Journal of Physiology, June 1, 1915, by Fawcett, Rogers, Rahe and Beebe;
3. The Journal of Pharmacology and Experimental Therapeutics, Vol. II, No. 6, July, 1911, page 507, by Voegtlin and Bernheim;
4. The Journal of Pharmacology and Experimental Therapeutics, vol. 13, No. 4, July, 1919, page 301, by Voegtlin and Myers;
5. Southern Medical Journal, Vol. XV, March, 1922, and Vol. XVI, November, 1923, by A. L. Levin.

All such previous extracts, however, so far as I am aware, have been ineffective or unsafe for continuous therapeutic use in really alleviating high blood pressure, or for relieving such subjective symptoms commonly associated with hypertension, such as headache, insomnia, nocturia, tinnitus, etc.; probably either because they have contained too little of the non-toxic blood-pressure-lowering substance to be of any real benefit, or because they have had such a high proportion of peptone, choline, histamine-like substances, protein split products, etc. (which are toxic blood-pressure-lowering substances,) that upon administration they have produced a violent and immediate toxic or shock effect,

which made them dangerous to use at all and impossible to use in sufficient quantity to produce the non-toxic blood-pressure-lowering effect or to relieve such subjective symptoms, even in single doses, not to mention the cumulative difficulties from repeated doses.

This situation has been complicated by the fact that the shock or toxic effect manifests itself in a sudden but temporary lowering of the blood pressure—that is, temporary in cases where this sudden effect is not fatal. This shock effect usually takes place within a few seconds after administration of the product, and if the amount of such impurities is sufficient it may sharply lower the blood pressure to a point where death occurs. This sharp lowering of the blood pressure in shock may be lessened by giving a smaller dose, so that such lowering will not reduce the blood pressure to the fatal point; in which case the blood pressure recovers from the shock within a few minutes, and returns to substantially what it was before the dose was given, or even higher. It is only subsequent to that that the non-toxic effect of the blood-pressure-lowering hormone or active principle is obtained, as such effect starts slowly and continues over a period of from several hours to several days. It is obvious that if the danger of the shock effect from the impurities makes it necessary to use small doses, such smallness of the dose will correspondingly reduce the later effect of the dose in the beneficial reduction of the blood pressure as distinguished from the sharp and short but dangerous shock effect.

In consequence of this, previous investigators, so far as I am aware, have not been able to obtain from the liver a substance which could be administered safely and repeatedly to produce a prolonged therapeutic effect of value in the treatment of hypertension; because they either did not obtain potent extracts, or did not obtain extracts sufficiently free from toxic impurities to make it possible to administer doses of sufficient size to give such desired prolonged therapeutic effects.

In contradistinction to this, I have obtained from the liver an extract which is

quite effective therapeutically in reducing high blood pressure and/or relieving certain subjective symptoms commonly associated with hypertension, such as headache, insomnia, nocturia, tinnitus, etc., over a fairly prolonged time, and one which can be used, and used repeatedly, without producing ill effects in the patient, and especially without producing any dangerous amount of shock. That is, the liver extract which I have produced is not only potent to reduce high blood pressure and/or to relieve such subjective symptoms, but can be given in doses of sufficient size to be therapeutically effective, because it is sufficiently free from proteins and other impurities so that any sudden shock-produced lowering in the blood pressure is relatively small, is not sufficient to reduce blood pressure to a point 20 dangerously lower than normal blood pressure, and is ordinarily not sufficient to make the sudden shock-produced lowering greater than the later and longer continued lowering which is the therapeutic effect of the 25 hormone.

In carrying out my invention, I may use liver from any available animals, as from hogs or beef. I mince or grind a quantity of such liver, either liver from freshly slaughtered animals or liver which has been immediately refrigerated after removal from freshly slaughtered animals and kept refrigerated until used. Then I extract this liver with a solvent which takes up from the liver the 30 desired blood-pressure-lowering hormone or active principle, or some substance containing it, and which, in addition, in some way either inhibits the deleterious action on such hormone or active principle of any copresent 35 destructive agents (such as proteolytic enzymes) or destroys such agents. The extract thus obtained, after being separated from the residual solid matter, is treated to remove the major portion of any undesirable 40 contents. While this treatment includes other steps, probably the most important part of the procedure is the separation of the undesirable matter, mostly protein matter, by fractionation with varying concentrations 45 of alcohol. The matter which is removed at alcoholic concentrations up to about 70% is discarded; but this 70% filtrate or the precipitate-fractions obtained at higher 50 alcohol concentrations, or both this filtrate and these precipitate-fractions, are preserved, as they contain at least a large part of the blood-pressure-lowering hormone or active principle. While this fractional precipitation with alcohol has removed a large 55 part of the undesirable matter, further treatment may also be given the preserved substances, for further purification.

In order that a better understanding of my invention may be obtained, I shall now

describe specifically a preferred process of producing my product.

A quantity of fresh liver, such as the liver from freshly slaughtered hogs or beef, is ground through a meat grinder, and mixed 70 with an equal volume of 95% ethyl alcohol, made slightly acid to litmus with hydrochloric acid. This mixture is allowed to stand in the ice-box for several hours, desirably overnight, to give time for the desired extraction. 75

The mixture is then filtered to remove the solid residue. This filtrate, which may be called filtrate No. 1, is then mixed with an equal volume of 95% alcohol; by which the alcohol concentration is raised. A precipitate, which may be called precipitate A, forms as a result of this increased alcohol concentration. 80

This precipitate A is suitably removed, as by filtration. To the resultant filtrate, which 85 may be called filtrate No. 2, is added an equal volume of 95% alcohol, which raises the alcohol concentration still higher.

Another precipitate forms as the result of this increased alcohol concentration; and this 90 precipitate may be called precipitate B.

This precipitate B is likewise suitably removed, as by filtration; but is preserved, as it contains a large part of the desired blood-pressure-lowering hormone. The filtrate 95 from this last precipitation, which filtrate may be called filtrate No. 3, is also preserved; as it also contains some of the desired hormone. Both precipitate B and filtrate No. 3 are desirably used as a basis for final extracts, 100 after additional purification if desired.

Thus the precipitate B may be dissolved in distilled water, usually of a volume of about one-twentieth of the volume of the original extracting liquid. This solution may be appropriately treated with various solvents which do not mix with water, in order that a still higher purification may be obtained. For instance, it may be so treated, separately, with ether, chloroform, amyl alcohol, lead acetate, and hydrogen sulphide. Any of these treatments and separations may be repeated several times, if desired; and, if desired, the treatments may be interspersed, as by having a treatment with ether first, then a treatment with chloroform, then several treatments with amyl alcohol, and then another treatment with ether. The aqueous solution thus obtained, which contains the hormone or active principle, is filtered to remove any precipitate or cloudiness, and the resultant filtrate used as the purified extract. 115

Likewise, the filtrate No. 3 may also be subjected to further purification. To this end, such filtrate is desirably evaporated to dryness in a water bath; and this residue treated in the same manner as is described above for precipitate B, to produce a final purified extract. 125

All the purified extracts which have been 130

thus obtained have been demonstrated to have a depressor action on the blood pressure in animals, and in man so far as they have been used in man. They have been used to 5 depress hypertension in man; and have been used in animals to counteract the effects of artificial hypertension, as produced both by pituitary extracts and by guanidine compounds. They not only reduce both natural 10 and artificial hypertension, but they can be given in sufficient doses to do this markedly without producing undue shock effect; and so are indicated in the treatment of hypertension.

15 I claim as my invention:—

1. The method of producing a blood-pressure-lowering substance from liver, which consists in extracting the liver with alcohol, and separating the blood-pressure-lowering 20 substance from much of the contaminating matter extracted with it by fractionation with varying concentrations of alcohol.

2. The method of producing a blood-pressure-lowering substance from liver, which 25 consists in extracting the liver with alcohol, separating the blood-pressure-lowering substance from much of the contaminating matter extracted with it by fractionation with varying concentrations of alcohol, and forming 30 a solution from a precipitate obtained at higher alcohol concentration.

3. The method of producing a blood-pressure-lowering substance from liver, which 35 consists in extracting the liver with alcohol, separating the blood-pressure-lowering substance from much of the contaminating matter extracted with it by fractionation with varying concentrations of alcohol, forming 40 solutions from precipitates obtained at higher alcohol concentration, and using both the solution and the filtrate remaining after a precipitation at a higher alcohol concentration as a basis for therapeutic extracts.

4. A substance derived from the liver and 45 having a prolonged blood-pressure-lowering effect when injected in cases of essential hypertension and a sufficiently small short-acting blood-pressure-lowering effect to enable doses of sufficient size to be given to produce such prolonged effect.

5. A substance derived from the liver and 55 having a blood-pressure-lowering effect, and sufficiently free from impurities so that it may without substantial danger be administered repeatedly in sufficient quantities to counteract excessive blood pressure.

6. A substance derived from the liver and 60 having a blood-pressure-lowering effect, and sufficiently free from impurities so that the shock effect from administering it in therapeutically effective doses to a patient with high blood pressure will not cause a sudden reduction in blood pressure to the danger point.

65 7. A substance derived from the liver and

having the property of reducing the subjective symptoms commonly associated with hypertension, such as headache, insomnia, nocturia, tinnitus, etc., and sufficiently free from contaminating substances so that it may 70 without substantial danger be administered in sufficient quantities to be therapeutically effective.

8. A preparation for parenteral administration comprising an extract of liver which 75 is capable of causing a prolonged reduction of arterial hypertension and which is practically free from injurious substances.

In witness whereof, I have hereunto set my hand at Kansas City this 7th day of 80 April, A. D. one thousand nine hundred and twenty six.
